(57) **CLAIM**

We claim the ornamental design for an anti-chafing patch, as shown and described.

DESCRIPTION

FIG. 1 is a perspective view of a first embodiment of our new design.

FIG. 2 is a front view of our new design shown in FIG. 1.

FIG. 3 is rear view of our new design shown in FIG. 1.

FIG. 4 is a left-side view of our new design shown in FIG. 1.

FIG. 5 is a right-side view of our new design shown in FIG. 1.

FIG. 6 is a top view of our new design shown in FIG. 1.

FIG. 7 is a bottom view of our new design shown in FIG. 1.

FIG. 8 is a perspective view of the first embodiment of our new design in use.

FIG. 9 is a front view of the first embodiment of our new design in use.

FIG. 10 is a rear view of the first embodiment of our new design in use.

FIG. 11 is a left-side view of the first embodiment of our new design in use.

FIG. 12 is a right-side view of the first embodiment of our new design in use.

FIG. 13 is a top view of the first embodiment of our new design in use.

FIG. 14 is a bottom view of the first embodiment of our new design in use.

FIG. 15 is a perspective view of a second embodiment of our new design.

FIG. 16 is a front view of our new design shown in FIG. 15 in use.

FIG. 17 is rear view of our new design shown in FIG. 15 in use.

FIG. 18 is a left-side view of our new design shown in FIG. 15 in use.

FIG. 19 is a right-side view of our new design shown in FIG. 15 in use.

FIG. 20 is a top view of our new design shown in FIG. 15 in use.

FIG. 21 is a bottom view of our new design shown in FIG. 15 in use.

FIG. 22 is a perspective view our new design shown in FIG. 15 in use.

FIG. 23 is a front view of our new design shown in FIG. 15 in use.

FIG. 24 is a rear view of our new design shown in FIG. 15 in use.

FIG. 25 is a left-side view of our new design shown in FIG. 15 in use.

FIG. 26 is a right-side view of our new design shown in FIG. 15 in use.

(Continued)

FIG. 27 is a top view of our new design shown in FIG. 15 in use.

FIG. 28 is a bottom view our new design shown in FIG. 15 in use.

FIG. 29 is a perspective view of our new design shown in FIG. 15 in use.

FIG. 30 is a front view of our new design shown in FIG. 15 in use.

FIG. 31 is rear view of our new design shown in FIG. 15 in use.

FIG. 32 is a left-side view of our new design shown in FIG. 15 in use.

FIG. 33 is a right-side view of our new design shown in FIG. 15 in use.

FIG. 34 is a top view of our new design shown in FIG. 15 in use.

FIG. 35 is a bottom view of our new design shown in FIG. 15 in use.

FIG. 36 is a perspective view of our new design shown in FIG. 15 in use.

FIG. 37 is a front view of our new design shown in FIG. 15 in use.

FIG. 38 is a rear view of our new design shown in FIG. 15 in use.

FIG. 39 is a left-side view of our new design shown in FIG. 15 in use.

FIG. 40 is a right-side view our new design shown in FIG. 15 in use.

FIG. 41 is a top view of our new design shown in FIG. 15 in use.

FIG. 42 is a bottom view of our new design shown in FIG. 15 in use.

FIG. 43 is a perspective view of our new design shown in FIG. 15 in use.

FIG. 44 is a front view of our new design shown in FIG. 15 in use.

FIG. 45 is a rear view of our new design shown in FIG. 15 in use.

FIG. 46 is a left-side view of our new design shown in FIG. 15 in use.

FIG. 47 is a right-side view our new design shown in FIG. 15 in use.

FIG. 48 is a top view of our new design shown in FIG. 15 in use; and,

FIG. 49 is a bottom view of our new design shown in FIG. 15 in use.

The broken lines showing a human figure in the drawings are for the purposes of depicting environment and form no part of the claim. All other broken lines depict portions of an anti-chafing patch and form no part of the claimed design.
